(57) **CLAIM**

The ornamental design for a buffet as shown and described.

DESCRIPTION

FIG. 1 is a perspective view of a buffet showing the new design;

FIG. 2 is a front elevational view of the buffet;

FIG. 3 is a rear elevational view of the buffet;

FIG. 4 is a left side elevational view of the buffet; the right side of which is a mirror image;

FIG. 5 is a top plan view of the buffet; and,

FIG. 6 is a bottom plan view of the buffet.

The broken line portions of the drawings are included to show portions of the buffet that form no part of the claimed design.
